ATTORNEY

UNITED STATES PATENT OFFICE.

RUDOLPH WAGNER, OF NEW YORK, N. Y.

DESIGN FOR A CABINET FOR COIN-OPERATED MACHINES.

SPECIFICATION forming part of Design No. 28,995, dated July 5, 1898.

Application filed June 11, 1898. Serial No. 683,233. Term of patent 7 years.

To all whom it may concern:

Be it known that I, RUDOLPH WAGNER, a citizen of the United States, residing at New York, (borough of Manhattan,) in the county 5 of New York and State of New York, have invented and produced a new and original Design for Cases for Coin-Operated Machines; and I do hereby declare the following to be a full, clear, and exact description of the invention, such as will enable others skilled in the art to which it appertains to make and use the same, reference being had to the accompanying drawings, and to letters of reference marked thereon, which form a part of this 10 specification.

The invention consists in the peculiar shape and ornamentation of a cabinet for coin-operated picture-displaying mechanism, as hereinafter described and claimed.

20 Figure 1 is a front elevation of a casing embodying the novel features of my design, and Fig. 2 is a side elevation of the same. Fig. 3 is a top or plan view of the cabinet; and Figs. 4 and 5 are horizontal sections of the cabinet, 25 taken, respectively, on lines 4 and 5 in said Fig. 2.

In order to render the description of my new design clear, I will first describe in detail the ornamental pedestal or support on 30 which is the ornamental box proper, and then I will describe the box, the whole forming the complete cabinet.

In the said drawings hereinabove set forth, A indicates the ornamental pedestal or support, the leading features of which are a square base or platform a , bounded by an ornamental molding a' , supported by four ornamental feet b , all of which are practically of a claw-shaped design. Extending upwardly from the middle of the platform or base a are the four plain side pieces a^2 of the post proper, and each corner of said square-shaped post has an ornamental bead-strip a^3 . The said post is smaller in cross-section than the upper surface of the base or platform a , whereby the combined effect of said base and the support or post thereon is greatly enhanced and the whole receives a massive and beautiful appearance. The said bead-strips a^3 , above mentioned, as will be seen from Figs. 1 and 2, terminate at the top in ornamental bracket-like parts a^4 , which are of the cyma

reversa or ogee configuration when viewed from the side. The edges of said bracket-like parts a^4 are also provided with the bead 55 ornamentations a^5 , which are continuous with the beads on the lower portions of the said strips a^3 . Against the front and the two sides of the said pedestal or support and resting also upon the upper surface of the base or 60 platform a at points midway between the bead-strips a^3 are the ornamental knee-pieces a^6 , which are of the cyma reversa or ogee configuration when viewed from the side and have edges ornamented with the beads a^7 . 65

I will now describe the ornamental box C, which is supported on the said pedestal A.

The leading features of the design of said box C are an ornamental base c , arranged directly upon the top of the pedestal. Said 70 base c is bounded on the front and sides with an ornamental molding c' , parts of which are provided with an egg-and-dart or echinus ornamentation. At the rear of said base c is a plain upright board c^2 , forming the back of 75 the box C, which is topped off with an ornamental molding c^3 of the same design as the molding c' , surrounding the base c . Extending forwardly from the front surface of said board c^2 are a pair of plain boards c^4 , both of 80 which are provided at their front edges with an ornamental turned bead c^5 . Said boards c^4 have an ornamental cover c^6 , and c^6 is an ornamental door hinged between the said boards c^4 , which is provided with an ornamental panel c^8 , surrounded by a turned bead c^{10} , as clearly represented in Fig. 1. The said top or cover c^6 is also surrounded on three sides by an ornamental molding c^7 of the egg-and-dart or echinus design and is provided 90 with a slot c^{11} . Upon the said ornamental cover or top c^6 there is a smaller ornamental box D, formed by a portion of the upright board c^2 , two side pieces d , a front piece d' , and an ornamental top or shelf d^2 . The edges 95 of the side pieces d are ornamented with turned beads d^3 , and the shelf or top d^2 has a slightly downwardly inclining part d^4 , bounded by an ornamental molding d^5 of the egg-and-dart or echinus design. Said box D 100 is smaller in width than the box C, whereby a shelf c^{12} is provided on the top of the cover c^6 . A pair of beaded knee-pieces d^6 of the cyma reversa form are placed upon the shelf

c^{12} and against the front piece d' of the box D, and upon the shelf or top d^2 of said box D, I have arranged a pair of beaded cove-pieces d^1 , which are contiguous to the board 5 c^2 and terminate close to the molding c^3 on the top of said board c^2 .

Having thus described my invention, what I claim as new, and desire to secure by Letters Patent, is—

The design for a cabinet, substantially as to herein shown and described.

In testimony that I claim the invention set forth above I have hereunto set my hand this 9th day of June, 1898.

RUDOLPH WAGNER.
